UNITED STATES PATENT OFFICE.

HARRY T. KRAKAU, OF CLEVELAND, OHIO, ASSIGNOR TO THE NATIONAL MALLEABLE CASTINGS COMPANY, OF CLEVELAND, OHIO, A CORPORATION OF OHIO.

CAR-COUPING.

1,123,130.

Specification of Letters Patent. Patented Dec. 29, 1914.

Application filed November 27, 1911. Serial No. 662,625.

To all whom it may concern:

Be it known that I, HARRY T. KRAKAU, a resident of Cleveland, in the county of Cuyahoga and State of Ohio, have invented 5 a new and useful Improvement in Car-Couplers, of which the following is a full, clear, and exact description, reference being had to the accompanying drawings, forming part of this specification, in which—

10 Figure 1 is a longitudinal vertical section of my improved coupler; Fig. 2 is a horizontal longitudinal section; Fig. 3 is a vertical cross-section showing the parts in locked position; Fig. 4 is a view similar to Fig. 3, showing the parts in lock-set position; Fig. 5 is a view similar to Fig. 3, showing the parts in the position where the knuckle is pulled open; Fig. 6 is a view similar to Fig. 3, showing the parts in 15 knuckle-thrown position; Fig. 7 is a front elevation of the lock lifter; Fig. 8 is a view similar to Fig. 3, showing a modification; and Figs. 9 and 10 are detail views of the locking block.

20 My invention relates to couplers of the usual vertical plane type having pivoted knuckles and preferably conforming to the usual Master Car Builders' contour and other United States standards.

25 The invention relates particularly to the coupler disclosed and claimed in my Patent No. 1,040,551, dated October 8, 1912, with which I also preferably employ the release mechanism between the lock and the lock lifter shown in my application Serial No. 35 575956, filed August 6, 1910.

30 One object of the present invention is to do away with the need for an internal shoulder in the coupling head to tilt the lock into 40 lock-set position, as shown in my co-pending application Serial No. 575956. This improvement makes it possible to reduce the necessary vertical height of the coupler head, which gives an important advantage.

45 The second point of difference is that in the present improved form, I lock-set the lock upon the knuckle tail. This avoids the necessity for making the various dimensions of the coupler cavity uniform in order to 50 insure lock-set of the lock. In other words, the head may be cast less accurately by the use of my present invention than in the case

where the lock-set was on a shelf or ledge in a coupler head, as in my application Serial No. 575956.

55

In the drawings, in which I show a preferred form of the invention.

2 designates a coupler head carried by a hollow shank 3.

4 designates the knuckle pivotally mounted on the pin 5. The hook or coupling portion 6 of this knuckle may be of substantially the usual form, but its tail portion is preferably modified by providing it with the curved or convex portion 7 and an enlarged rear portion 8 having a face 9 preferably inclined at about 45° to the angle of draft and engaging a corresponding surface 10 in the coupler head. The purpose of this wedge-shaped tail with rearwardly diverging sides is to transmit pulling strains directly to the coupler head and lock, and relieve the pin 5 from strains. The rear end of the knuckle tail is preferably curved, as shown, and the rear side of the knuckle cavity is closed by the wall 12.

70 The lock 13 is preferably of the form shown in Figs. 9 and 10. It is preferably a solid vertically movable and tilting block which is rectangular in cross section. Its upper surface is higher in one portion than another, the highest portion being shown at 14 and formed by two inclines forming an apex. The bottom of this block is preferably provided with a depending lug or projection 15 which co-operates with the knuckle tail in the manner hereinafter described.

75 The lock is also provided with a rearward or laterally projecting lug 16 on its rear side, said lug co-operating with the slot 17 in the lock lifter 18. The various positions of this lug 16 and slot 17 are shown in dotted lines in Figs. 3, 4, 5 and 6, which represent, respectively, the locked, lock-set, knuckle pulled-open, and knuckle-thrown positions

80 90 95 of the knuckle. In the locking position the lock seats between the straight edge of the knuckle tail and the opposite wall of the knuckle cavity which is preferably recessed as at 19 to seat and guide the lock. The side of the lock engaging the locking face of the coupler is tapered downwardly, as best

100 shown at 20 in Fig. 3, so as to give it a wedging action and also cause it to free

more rapidly when lifted. The abutting wall of the coupler head has a corresponding inclination, as shown in Figs. 3 to 6.

The lock lifter 18 in the form of all the figures, except Fig. 8, is shown as adapted for top lift, it having an eye 18^a for attachment of the uncoupling mechanism. The slot 17 therein has an upward lateral extension 17^a of proper shape to receive the lug 16 of the locking block, a shoulder 21 being provided between the two parts of the recess. At its lower end, the lifter is provided with an upwardly projecting lateral hook 22 co-operating with the knuckle-throwing mechanism for the purpose hereinafter described.

In the locked position shown in Fig. 3, the upper wall of the slot 17^a rests upon the lug of the lock which supports the lifter. An upward pull upon the lifter causes the bottom wall 23 of the recess 17^a to engage the lower surface of the lock lug, thereby lifting the lock. A continued pull upon the lifter carries the lock upwardly until the hump or wedge 14 at the top of the lock strikes the top wall of the coupler cavity, as shown in dotted lines in Fig. 4. The continued lifting will then cause the block to tilt so that its lower edge will swing to the left, as shown in Fig. 4, in a position over the knuckle tail. In this movement the upper right hand corner of the block will move to the right and strike the right hand wall, the tilting being caused by the lifting power being applied at one side of the center of gravity and the block fulcruming on the top of the wall of the coupler cavity. Upon release of the lifter, the block will drop slightly and rest upon the inner edge of the knuckle tail, as shown in Fig. 4.

It will be noted that the tilting of the lock to lock-set is obtained without any inner shoulder in the coupler cavity, thus reducing the height of the cavity; while at the same time the lock-set is on the knuckle tail itself. This latter feature enables the coupler cavity to be made less accurately at the same time securing proper functioning and operation.

In the movements just described, when the lock strikes the upper wall of the head and is caused to tip laterally, its lug 16 moves to the left within the slot in the lock lifter and is drawn underneath the shoulder 21 in the upper wall of the slot. The lug is now in such a position that its lower surface is disengaged from the shoulder 23, whereby leaving the lock lifter free to continue its vertical movement, if desired, for throwing the knuckle without engaging and further lifting the lock. In other words, the lock lifter disconnects from the lock in this stage of the operation allowing further upward movement of the lock lifter without moving the lock.

The means by which the throwing of the

knuckle is accomplished forms no part of my present invention, but the particular form of knuckle throwing device in the drawings is the invention of J. P. Kittredge, and is covered in his Patent No. 1,063,544, dated June 3, 1913. The knuckle-throwing connections for the lifter may be as shown in my own copending application Serial No. 575,956; but in the form here shown they consist of the Kittredge form. In this form 24 is a bell crank lever journaled at the under side of the coupler head, preferably in a lug or eye 25 thereof and having a bent portion 26 engaged by the U-shaped portion 22 of the lock lifting member. The other arm of the bell crank extends down and engages the rearwardly extending eye 27 of the lever 28. The bell crank lever 24 rotates in a vertical plane while the lever 28 rotates in a horizontal plane. The forwardly projecting arm of lever 28 has a hook portion 29 engaging the opening of a lug 30 formed integral with the lower side of the coupler nose. Rotation of the lever 28 on its axis throws the knuckle outwardly and thereby opens it, and in the preferred form the lever 28 is preferably rotated on the face of a stirrup 31. During the raising of the lock lifter after lock setting, the knuckle tail will pass beneath the flat lower surface of the lock, raising the lock from its inclined position, shown in Fig. 4, until it assumes the position shown in Fig. 6, where it is squarely supported upon the upper surface of the knuckle tail.

In Fig. 5 I show the "knuckle pulled-open" position which the parts take if the operator lock-sets the lock and the cars are then pulled apart or the knuckle is pulled open by hand. As shown in Fig. 6, in the knuckle-thrown position, the lug 16 is near the bottom of the slot 17, while as shown in Fig. 5 it is within the slot portion 17^a in the knuckle pulled-open position.

With the parts as shown in Fig. 6 when the lock lifter and knuckle thrower is released, the lifter will drop until the upper wall of the slot rests upon the lug 16, as shown at 17^a, as substantially shown in Fig. 5 when the lock lifter will be carried by the lock. If now the knuckle is closed either by hand or in coupling with another car, the lock rests upon the upper surface of the knuckle tail, but the knuckle tail slides under it and will not carry or drag the lock over with it to the left. The reason for this is that the lug 16 will engage the shoulder 21 in the upper slot portion 17^a, this engagement preventing the lock from being frictionally dragged to the left as it would be liable to be so moved by the movement of the knuckle tail, except for the resisting influence of the lug and shoulder just mentioned. The knuckle tail continues to close until it has become completely disengaged

from the lower left hand corner of the lock, at which time, the lock then drops vertically, allowing the lifter to drop with it and seating again as a wedge, as shown in Fig. 3. This last described action will take place upon closing the knuckle in either position shown in Fig. 5 or that shown in Fig. 6. If, after lock-setting in the position shown in Fig. 4, the lifter is not further lifted up, it will remain further supported on the lug of the lock; and if the knuckle is pulled open either by hand or in uncoupling, the knuckle tail will slide under the lock and support it thereon.

It will be noted that although the lock is at the same elevation in Fig. 5 as in Fig. 6, it lies at a point farther to the right in Fig. 5 than it does in Fig. 6, it being prevented from moving to the right in Fig. 6 by the lug 16 engaging the vertical wall in the lower portion of the lifter slot.

Referring now to Fig. 6, if the lifting force which has hitherto actuated the lifting member 18 is released, the lifter will slide downwardly within the head until the projection 21 in the upper part of the lifter slot rests upon the lug 16. This is not a desirable position, for if the knuckle tail were now closed (omitting the function of lug 15), the shoulder 21 could not act as a stop to prevent the lock from being frictionally dragged to the left out of its proper position. It is, therefore, desirable to provide means for shifting the lock slightly to the right during the initial closing movement of the knuckle so that its lug 16 will enter the upper right-hand portion 17^a of the lifter slot and engage the shoulder 21. Such lateral shifting is performed during the initial closing of the knuckle by the action of the rear edge of the knuckle tail, which, before sliding completely under the lock, comes in contact with the depending lug 15 and thereby gives the lock a slight push to the right, the lifter having at this time dropped to its lowermost position, where its shoulder 21 rests on the top of lug 16. The edge portion of the tail which acts upon lug 15 is shown at α in Fig. 2. The shifting of the lock to the right in the upper portion of the lifter recess will cause the lug 16 and the shoulder 21 to come into engagement so that upon further closing movement of the knuckle tail the frictional dragging of the lock to the left is prevented by the engagement of its shoulder with the lug, as already described.

In Fig. 8, I show a form in which the lifter is arranged to be operated from the bottom. For this purpose, it has a lower eye 32, through which a chain may extend to a lever or other operating device by which, through a lengthwise pull on the chain, the lifter may be moved up to carry out the same operations as in the top lift

form. In this form, the upper part of the lifter above the slotted part is done away with, and the top of the coupler is preferably closed, the lifter moving up and down within the coupler cavity.

The advantages of my invention result particularly from the modifications in the mode of lifting and locksetting. Also from the means of preventing frictional dragging of the lock by movement of the knuckle tail. By doing away with any internal shoulder for tilting the lock, I am enabled to reduce the vertical height of the coupler head; while by lock-setting on the knuckle tail I avoid the necessity for accurate shaping of the interior cavity of the coupler head. The prevention of dragging the lock with the knuckle tail avoids carrying the lock into position where it would not drop properly when released.

Many changes may be made in the form and arrangement of the coupler and its parts, the means for knuckle-throwing, etc., without departing from my invention.

I claim:—

1. A car coupler having a pivoted knuckle, a lock adapted to bear on one side against the front face of the knuckle tail and on the other side against a side wall of the coupler, a lifter, and a lug and recess engagement between the lock and the lifter, a raised portion on the lock and the lifter, to coöperate with the top of the coupler cavity to release said engagement and to lock-set the lock on the knuckle tail, the said lifter having a further upward movement after disengagement from the lock to actuate the knuckle.

2. A car coupler having a pivoted knuckle, a lock adapted to bear on one side against the front face of the knuckle tail and on the other side against a side wall of the coupler, a lifter, a lug and recess engagement between the lock and the lifter, a shoulder in the recess, to prevent lateral movement of the lock and to hold it in alinement to drop by gravity into locking position.

3. A car coupler having a pivoted knuckle, a lock being adapted to bear on one side against the front face of the knuckle tail and on the other side against a side wall of the coupler, a lifter, a lug and recess engagement between the lock and the lifter, a shoulder in the recess to prevent lateral movement of the lock and to hold it in alinement to drop by gravity into locking position, and a projection on the bottom side of the lock adapted to bear against the knuckle tail when the knuckle is in open position and coöperating with the said shoulder to prevent lateral movement of the lock.

4. A car coupler having a pivoted knuckle, a lock adapted to bear on one side

against the front face of the knuckle tail and on the other side against a side wall of the coupler, a lifter, and a lug and recess engagement between the lock and the lifter, the raised portion on the lock being adapted to coöperate with the top of the coupler cavity to release said engagement and lock set the lock and to permit a further movement of the lifter without further raising

the lock for actuating knuckle throwing 10 mechanism.

In testimony whereof, I have hereunto set my hand.

HARRY T. KRAKAU.
